[57] CLAIM

The ornamental design for a pair of hand rakes, as
shown and described.

DESCRIPTION

FIG. 1 is a perspective view of a pair of hand rakes showing my new design;

FIG. 2 is a side elevational view of the left-hand portion thereof, with the side opposite being substantially similar in appearance and the right-hand element being a mirror image thereof and omitted for clarity of illustration;

FIG. 3 is a bottom plan view of the left-hand portion thereof, with the right-hand portion being a mirror image of that shown and omitted for clarity of illustration;

FIG. 4 is a rear elevational view of the left-hand portion thereof, with the right-hand portion being a mirror image of that shown and omitted for clarity of illustration;

FIG. 5 is a top plan view of the left-hand portion of a second embodiment thereof, with the right-hand portion being a mirror image of that shown and omitted for clarity of illustration, the only difference residing in the prong configuration;

FIG. 6 is a top plan view of the left-hand portion of a third embodiment thereof, with the right-hand portion being a mirror image of that shown and omitted for clarity of illustration, the only difference residing in the prong configuration; and

FIG. 7 is a top plan view of the right-hand portion of a fourth embodiment thereof, with the left-hand portion being a mirror image of that shown and omitted for clarity of illustration, the only difference residing in the prong configuration.
